UNITED STATES PATENT OFFICE.

CHARLES F. SCHELL, OF BUFFALO, NEW YORK, ASSIGNOR TO JAY T. BADGLEY, OF DUNKIRK, NEW YORK.

STAND FOR GARBAGE AND OTHER RECEPTACLES.

1,137,355.

Specification of Letters Patent. Patented Apr. 27, 1915.

Application filed March 28, 1914. Serial No. 827,835.

To all whom it may concern:

Be it known that I, CHARLES F. SCHELL, a citizen of the United States, residing at Buffalo, in the county of Erie and State of New York, have invented new and useful Improvements in Stands for Garbage and other Receptacles, of which the following is a specification.

This invention relates to a stand or supporting frame for garbage and similar receptacles, and more particularly to stands of this character provided at their top with a hinged cover for closing the receptacle, and a treadle or foot-lever for opening the cover.

The purpose of my invention is to improve the construction of such stands and the cover-operating devices with a view of simplifying them, reducing their cost of manufacture, and rendering them compact and neat in appearance, such receptacles being often kept in vestibules, kitchens and other indoor places where space is limited.

In the accompanying drawings: Figure 1 is a sectional elevation of a stand embodying the invention and showing the garbage receptacle in place therein. Fig. 2 is a rear view of the stand with the receptacle removed. Fig. 3 is a bottom plan view of the stand and the receptacle. Fig. 4 is an enlarged cross section of the lid-arm on line 4—4, Fig. 1.

Similar characters of reference indicate corresponding parts throughout the several views.

1 indicates the metallic can or receptacle for the garbage, ashes or other material, which may be of any suitable form but is preferably straight or cylindrical, as shown.

40 It may have a bail 2 pivoted to fold into it, as shown by dotted lines in Fig. 1.

The stand or frame which contains and supports the garbage receptacle 1 may be of any suitable construction, but it is preferably of open or skeleton form, as shown in the drawings, to prevent the accumulation or lodgment of garbage therein and render the device sanitary. The stand shown in the drawings is of cylindrical form 50 to correspond to that of the garbage receptacle and comprises an upper horizontal ring 3, a lower horizontal ring 4, upright bars 5, 6, 7 and 8 connecting said rings at suitable intervals, and braces 9 secured to

and extending across said bottom ring 4 55 and forming supports for the receptacle. These bars are secured to said rings by rivets or other suitable fastenings and their upper ends terminate at the top ring 3, while their lower portions extend a suitable 60 distance below the bottom ring 4, to form the legs 10 of the stand by which the receptacle is supported at a sufficient distance above the ground to leave room for the lid-operating treadle hereinafter described. 65

11 indicates the lid or cover for the garbage receptacle 1 which is hinged at one side to the upper portion of the stand or frame and which in its closed position rests upon the open upper end of the receptacle, 70 the latter extending a sufficient distance above the top ring 3 of the stand for this purpose. The lid preferably has a depending marginal flange 12 which overlaps the receptacle and also an internal chamber or 75 receptacle 13 adapted to contain a suitable disinfectant. This chamber is provided in its bottom with perforations 14 through which the disinfectant enters the receptacle, and in its top with a filling opening closed 80 by a screw cap 15.

In the construction shown in the drawings, the lid is provided at its rear side with a projecting arm or lug 16 which is pivoted at its outer end upon a horizontal hinge-pin 85 or pintle 17 supported in eyes 18 carried by brackets 19 arranged on opposite sides of said arm. These brackets are secured to the rear upright bars 6 and 7 of the stand which bars are closely spaced for this purpose, as best shown in Figs. 2 and 3. The brackets consist of horizontal lower portions and upright portions arranged at the outer ends of said horizontal portions and having their upper ends curled to form the eyes 18. 90 As shown in Fig. 1, the arm 16 may be U-shaped or depressed below the top of the lid and the pintle 17 in the closed position of the lid, so that the latter, after having been opened and released, will have a tendency to drop forwardly upon the garbage receptacle. To stiffen or reinforce the arm 16, a brace 20 may be extended over the top thereof. In the construction shown, this arm and its brace are formed in one piece 100 by doubling a strip of sheet metal of the proper length around the hinge-pintle 17 and riveting or otherwise securing its su-

perposed branches or end portions to the lid, as shown at 21, producing a strong, simple and inexpensive construction.

22 indicates a foot lever or treadle arranged underneath the raised bottom of the stand and fulcrumed between its ends on a horizontal pivot pin 23 carried by hangers 24 depending from the braces or supports 9. The front portion 25 of this lever which is engaged by the foot of the operator extends a short distance beyond the front side of the stand, while its rear end is connected with the lid-arm 16 by a thrust rod or bar 26 in such a manner that when the front end of 10 the lever is depressed, the lid is opened, as shown by dotted lines in Fig. 1. In the open position of the lid, the upper portion of the thrust-bar bears against the underside of the lid-arm 16, forming a stop which 15 limits the opening movement of the lid. In the construction shown in the drawings, the end portions of the thrust bar are reduced and passed through slots 27 and 28 in the lever and the lid-arm, the shoulders 29 and 20 30 formed by reducing said bar bearing against said parts to transmit motion from the lever to the lid-arm. The reduced portions of this bar may be confined in said slots by bending the ends of the bar at an 30 angle, as shown in the drawings, or by other suitable means.

In the use of the device, the lid is raised by depressing the foot-lever and the garbage

receptacle is placed in the stand or frame. Upon releasing the lever, the lid drops to 35 its closed position upon the receptacle by gravity, making it unnecessary to manipulate the lid and rendering the device very convenient and insuring the closure of the receptacle at all times. When filled the receptacle can be as readily removed, after 40 opening the lid.

Aside from the convenience and the sanitary construction of the apparatus, its lid-operating device is direct in action and comprises a minimum number of parts, thus correspondingly reducing its cost.

I claim as my invention:

A stand for garbage receptacles and the like, comprising a frame constructed to receive and support the receptacle, a lid for said receptacle having a projecting arm hinged to the top of said frame, a single foot-lever pivoted between its ends to the underside of said frame, and a thrust-bar 55 pivotally connected at its lower end to the rear end of said lever and having its upper end pivoted to said lid-arm between the lid and the hinge-end of the arm.

Witness my hand this 24th day of March, 60
1914.

CHARLES F. SCHELL.
